UNITED STATES PATENT OFFICE

148,539

DESIGN FOR A CONCRETE MIXER

Louis G. Hilkemeier, West Allis, Wis., assignor to
Chain Belt Company, Milwaukee, Wis., a corpora-
tion of Wisconsin

Application March 21, 1946, Serial No. 127,735

Term of patent 14 years

(Cl. D14—3)

To all whom it may concern:

Be it known that I, Louis G. Hilkemeier, a citizen of the United States of America, residing at West Allis, county of Milwaukee, State of Wisconsin, have invented a new, original, and ornamental Design for Concrete Mixer, of which the following is a specification, reference being had to the accompanying drawings, forming part thereof.

In the said drawings:

Fig. 1 is a side elevation of a concrete mixer mounted on a motor truck showing my new design;

Fig. 2 is a rear elevation of the design shown by Fig. 1;

Fig. 3 is a perspective view of the design.

The portion shown in broken lines in Figs. 1

and 2 of the drawing is for illustrative purposes only.

I claim:

The ornamental design for a concrete mixer, substantially as shown and described.

LOUIS G. HILKEMEIER.
